(57) **CLAIM**

The ornamental design for a portable speaker system with clock, as shown and described.

DESCRIPTION

FIG. 1 is a top, front, right side, perspective view of a portable speaker system with clock in a closed condition showing my new design;

FIG. 2 is a bottom, front, left side, perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a top, front, right side perspective view thereof in an open condition;

FIG. 10 is a front view thereof;

FIG. 11 is a rear view thereof;

FIG. 12 is a top view thereof;

FIG. 13 is a bottom view thereof;

FIG. 14 is a left side view thereof;

FIG. 15 is a right side view thereof; and,

FIG. 16 is a cross sectional view thereof along line 16—16 in FIG. 3.

The broken lines in the drawings illustrate environmental material that forms no part of the claimed design.
